UNITED STATES PATENT OFFICE.

ALEXANDER CHISHOLM, OF ST. CLOUD, MINNESOTA.

AUTOMATIC STORM-SASH LIFTER.

Application filed February 11, 1922. Serial No. 535,779.

To all whom it may concern:

Be it known that I, ALEXANDER CHISHOLM, a citizen of the United States, residing at St. Cloud, in the county of Stearns and State 5 of Minnesota, have invented certain new and useful Improvements in Automatic Storm-Sash Lifters; and I do hereby declare the following to be a full, clear, and exact description of the invention, such as will enable others skilled in the art to which it 10 pertains to make and use the same.

This invention relates to new and useful improvements in storm sash openers, and has for its primary object the provision of 15 means adapted to automatically open and close a storm sash by the opening and closing of the sash of the window to which the storm sash is applied and thereby obviate the necessity of a person having to open and 20 close the storm sash independently of the window sash as now customary, and also said means forms an effective lock for the storm sash when the window sash is locked.

Another object of this invention is the 25 provision of a storm sash lifter or opener of the above stated character which will be simple, durable and efficient, and which may be manufactured and sold at a comparatively low cost.

With these and other objects in view, as 30 will become more apparent as the description proceeds, the invention consists in certain novel features of construction, combination and arrangement of parts as will be 35 hereinafter more fully described and claimed.

For a complete understanding of my invention, reference is to be had to the following description and accompanying drawings, in which:

Figure 1 is a sectional view illustrating 40 an automatic storm sash lifter or opener constructed in accordance with my invention.

Figure 2 is a sectional view taken on the line 2-2 of Figure 1,

Figure 3 is a front elevation illustrating a guide,

Figure 4 is a detail sectional view, illustrating 50 the stop formed by the upper end

of the guide, and taken on the line 4-4 of Figure 3,

Figure 5 is a detail sectional view taken on the line 5-5 of Figure 3, and

Figure 6 is a detail sectional view illustrating 55 the connection between the window sash and the operating rod.

Referring in detail to the drawings, the numeral 1 indicates a window frame of a well known construction having the usual 60 upper and lower window sashes 2 and 3 that are mounted for sliding movement so that the window may be opened and closed as desired. A storm sash 4 has its upper end secured to the window frame 1 by hinges 5, 65 while its lower end engages the sill 6 of the frame 1. The foregoing description relates to a well known window construction to which my invention is applied for the purpose of opening and closing the storm sash 70 4 by the opening and closing of the lower sash 3 of the window.

My invention comprises an actuating rod 7 that has one end pivotally, removably and 75 adjustably connected to the lower rail of the lower sash 3 by a channel iron bracket 8, while the other end of said rod is angularly bent to form a roller axle or journal 9 and on which is mounted a roller 10 operable against a guide 11 secured to the storm 80 sash 4 or to one of the side rails of the latter. The guide 11 comprises separable plates arranged at right angles to each other and detachably connected by tongues 12^a and one of said plates is provided with a slot 85 12 through which the axle 9 extends. The guide 11 is secured to the storm sash by screws or like fasteners 14, and when it is desired to remove the device from the storm sash, the rod 7 is unfastened from the 90 bracket 8 and the plate 11^a having the slot 12 is tilted to remove the tongues from the slots that are in the other plate 11^a, consequently freeing the plate 11^a which is at right angles to the storm sash with the rod 95 7 so that said parts may be stored away independently of the storm sash. The actuating rod adjacent to the axle 9 is provided with an arm 16 which is angularly bent to form a journal for a roller 17 and the latter 100

is spaced slightly from the roller 10 and is adapted, during the initial movement of the actuating rod, to come in engagement with an inclined guide 18 secured to the window frame 1 for the purpose of causing a direct outward pressure to be exerted on the storm sash on the initial movement of the lower sash 3 into an open position and this outward pressure or force is for the purpose 5 of releasing the storm sash in case the latter is slightly wedged or stuck in the window frame. During the final movement of the lower sash 3 into an open position, the actuating rod assumes a horizontal position, as 10 15 shown in dotted lines in Figure 1, with the roller 17 engaging the stop 15 formed by the rounded end of the plate 11^a which has the slot 12 to obviate any possible chance of the roller supporting end of the actuating 20 25 rod from sliding downwardly in the slot 12 of the guide when the actuating rod is disposed horizontally or in case the pivoted end of the actuating rod is slightly higher than the roller end, consequently obviating any 30 possibility of the storm sash falling into a closed position when the lower sash 3 is in a fully opened position. The roller 17 also rides against the outer edge of said last plate 11^a during the upward and outward movement of the rod.

With the parts in the position shown in full lines by Figure 1, it is impossible to swing the storm sash 4 outwardly or into an open position, owing to the actuating rod 7 being in engagement with a guide roller 19 journaled to the frame 1, and also this guide roller is adapted to bring about an effective closing of the storm sash when the lower window sash 3 is in a fully closed position. 35 40 A person desiring to ventilate the room raises the lower sash 3 in an upward direction and this movement causes the storm sash 4 to swing outwardly of the window frame, owing to the actuating rod 7 being pivoted to the lower sash 3 and the rollers 10 and 17 engaging the guide 11 and also the roller 17 engaging the guide 18. Sliding movement of the actuating rod 7 in respect to the guide 11 is limited by the axle 9 of 45 50 the roller 10 coming in contact with the upper end of the slot 12, thereby causing an outwardly forcing action against the sash 4, and as the lower sash 3 reaches its fully open position, the actuating rod assumes a horizontal position with both of the rollers in 55 60 engagement with the guide thereby forming an effective support for the storm sash 4 when in an open position. Also, the roller 17 being in engagement with the stop 15 obviates any possibility of the roller end of the actuating rod sliding downwardly in the slot 12 and permitting the storm sash to move towards a closed position. It is to be understood that in actual practice, a pair of

these devices will be applied to the side rails 65 of a storm sash and also to the side rails of the lower sash so as to provide an effective opening means to each side of the storm sash as well as forming an effective support for each side of the storm sash when in an open 70 position.

While I have shown and described the preferred embodiment of my invention, it will be understood that minor changes in construction, combination and arrangement of 75 parts may be made without departing from the spirit and scope of the invention as claimed.

Having thus described my invention, what I claim is:

1. The combination with a window frame having a slideable sash and a storm sash hinged thereto, of a guide secured to the storm sash, an actuating rod pivoted to the slideable sash, a roller carried by said actuating rod and engaging the guide, and means on the guide to be engaged by the roller to prevent the movement of the actuating rod in one direction when the storm sash is open. 80 85

2. The combination with a window sash and a storm sash, of a guide secured to the storm sash, an actuating rod pivoted to the window sash, a roller carried by said actuating rod to engage the guide, a second guide, and means carried by the actuating rod to engage the second guide during the early stages of the movement of the window sash towards an open position to cause the actuating rod to apply a direct force against the storm sash in an outward direction. 90 100

3. The combination with a window sash and a storm sash, of an actuating rod pivoted to the window sash and slidably connected to the storm sash, an inclined guide located between the sashes, and a roller carried by 105 the actuating rod to engage said inclined guide.

4. The combination with a window sash and a storm sash, of a guide carried by the storm sash, an actuating rod connected to the window sash and having a limited sliding connection with the guide, a roller carried by the rod and engaging the guide, an inclined guide, a second roller on said rod engaging the guides during the early stage 110 115 of the movement of the rod, and a stop on the guide to be engaged by the second roller to prevent the rod from sliding downwardly with respect to the first guide when the sashes are in opened position. 120

5. A storm sash operating mechanism comprising a guide adapted to be secured to a storm sash, said guide having a longitudinal slot, a rod adapted to be pivotally connected to a window sash, a second guide adapted to be secured to a window frame in an inclined position, a roller carried by said rod at its free end and adapted to move in 125

the slot in said guide, a second roller carried by said rod adjacent said first roller, and said second roller adapted during the early stages of its movement to engage said inclined guide to direct said rod outwardly with relation to the window sash to which it is to be attached.

In testimony whereof I affix my signature in presence of two witnesses.

ALEXANDER CHISHOLM.
